His Attorney.

UNITED STATES PATENT OFFICE

WILLI DOEBKE, OF BERLIN, GERMANY, ASSIGNOR TO GENERAL ELECTRIC COMPANY,
A CORPORATION OF NEW YORK

METHOD AND MEANS FOR ELIMINATING DISTURBING CURRENTS

Application filed March 14, 1929, Serial No. 347,105, and in Germany March 29, 1928.

My invention relates to a method and means for eliminating disturbing currents in circuits, such as those used for telephony or telegraphy which result from electromotive forces induced therein from conductors in the neighborhood of the circuit in question as from adjacent conductors of a power distribution system.

Potentials induced in the long distance conductors of a circuit of the type indicated from adjacent power conductors may be of sufficient magnitude to endanger the attendants at the telephone stations and operators of telephone equipment. These induced potentials also produce currents, resulting from the difference of potential between the two conductors of a single telephone circuit, or between the two circuits of a four wire phantom circuit due to asymmetries therein which are effective in the signal instruments of the respective circuits and thereby disturb the transmission of signals. That is, the effect of potentials induced with respect to ground in the two conductors of the circuit are likely to be unequal and thereby cause currents to flow from one conductor to the other through the signal equipment. These asymmetries may be normally present such as those due to the construction of the circuit or present momentarily during abnormal conditions. It has been found, for instance, in telephone circuits, that the higher harmonics of the inducing currents in the power circuit produce disturbing noises in the signal equipment.

The potential with respect to ground which is produced at either end of a conductor such, for example, as those of the well known four wire phantom arrangement may be represented by the equation

$$V = I \frac{m}{p} \cdot \tan \frac{p}{2}$$

where V is the potential with respect to ground; I is the inducing current; m is the mutual inductance per unit of length between the signal conductor and that which carries the inducing current, L is the length of the telephone conductor in inductive relation with the including circuit, and p is the propagation constant of the conductors, all of the

conductors being considered as connected in parallel with respect to the induced potential between the conductors and earth.

From the above equation it will be apparent that the value of the potential with respect to earth at either end of a conductor in question can never exceed a limiting value equal to $I \frac{m}{p}$ since as the length of the conductor

increases the value of $\tan \frac{p}{2}$ approaches one.

The object of my invention is to provide a signaling circuit of the type indicated which is so constructed and arranged that the value of propagation constant p , all of the conductors being considered as connected in parallel with respect to the induced potential with respect to earth, is such that potential V may be maintained negligible or at a value which may be tolerated, but in which the propagation constant of the signal circuit in which the conductors carry signal currents in opposite directions is not materially affected.

The novel features of my invention are set forth with particularity in the appended claims. My invention itself, however, both as to its organization and method of operation, may best be understood by reference to the following description taken in connection with the accompanying drawing in which the single figure illustrates a circuit constructed in accordance with my invention.

Referring to the drawing I have represented at 1 and 2 the conductors of a telephone circuit extending between stations A and B for the purpose of interconnecting signaling equipment located therein. This circuit includes transformers 3 and 4 located at the respective stations, one winding of each of which is connected to the signal equipment and the other winding to the line conductors 1 and 2. Similarly 5 and 6 represent the conductors of an additional telephone circuit extending between the stations A and B and connecting signaling apparatus therein through transformers 7 and 8. 9 and 10 represent transformers connected in an additional circuit arranged in phantom relation with the circuits 1 and 2, and 5 and 6; that is,

the secondary of the transformer 9 at the station A is connected between the midpoint on the secondary winding of transformer 7 and the midpoint on the secondary winding of the transformer 3, and, similarly, the corresponding winding of the transformer 10 is connected between the midpoints of the windings of transformers 4 and 8 which are connected to the line conductors. Thus signaling currents caused by potentials induced on the secondary winding of the transformer 9 flow in one direction through conductors 1 and 2 connected in parallel, winding of transformer 10 and thence through conductors 5 and 6 in parallel to the opposite side of the secondary winding of transformer 9, this arrangement comprising the well-known phantom circuit.

Any potentials induced in the different line conductors due to currents in adjacent power circuits will appear in all of the conductors in magnitudes dependent upon the relation of the different conductors to the inducing circuit and the effect of these potentials will be dependent on the asymmetries of the different conductors. With respect to these potentials the different conductors may be considered as connected in parallel relation. Considering first the circuit 1, 2 to increase the propagation constant with respect to these induced currents without at the same time increasing the propagation constant of the circuit, inductively related coils 11 and 12 arranged on a core 13 are inserted in the conductors at suitable points along the length thereof. These windings are both wound upon the core in the same direction so that with respect to circuit currents flowing in the conductors 1 and 2 as, for example, currents produced by telephone instruments at either of the stations, the different windings produce equal and opposing fluxes in the core. Thus the impedance of the circuit with respect to these circuit currents is not materially affected by these windings. With respect to currents which are induced in the conductors 1 and 2 from adjacent power circuits, for example, these currents are not equal and opposite in the two coils, as in the previous case, and hence produce fluxes in the core. Accordingly these windings materially increase the impedance with respect to these currents. Thus the effect of the coils 11 and 12 is to increase the propagation constant, and therefore the impedance, of the conductors with respect to the induced currents without, at the same time, increasing the propagation constant or impedance of the conductors with respect to the circuit currents. The same arrangement may be employed in the circuit 5, 6.

Where the phantom arrangement is employed, the disturbing currents in the phantom circuit may similarly be reduced by arranging the coils 14 and 15 of the conductors

5 and 6 upon the same core as coils 11 and 12 of the circuit 1, 2, all of these coils being wound in the same direction about the core; that is, so that currents which flow in the different conductors in unequal magnitudes, or in the same direction, as due to induced potential, will produce fluxes in the core, whereas fluxes produced in the core by coils 11 and 12, due to phantom circuit currents, will be equal and opposite to fluxes produced by the coils 14 and 15. Thus the impedance and propagation constant of the conductors considered as conductors arranged in parallel with respect to the induced potential will be materially increased, whereas the propagation constant of either of the circuits 1, 2 and 5, 6 or the phantom circuit is not materially increased.

The units comprising coils 11, 12, 14 and 15 wound upon core 13 may be placed at equal distances along the line and, if desired, at the points at which the Pupin coils are located. Thus any leakage reactance in these coils may be considered in connection with the construction of the Pupin coils. At 16 a second of these units is indicated in the drawing. The unit 11, 12, 13, 14, 15 is shown conventionally in the drawing and may comprise a core of any suitable form having windings arranged thereon in suitable manner.

What I claim as new and desire to secure by Letters Patent of the United States is:

1. The method of eliminating the effect of disturbing currents in an electric circuit produced by current carrying circuits located in proximity thereto which includes increasing the impedance of the conductors considered as connected in parallel with respect to the induced potential without materially increasing the impedance of the conductors with respect to desired currents in said electric circuit.

2. In combination, an electric circuit comprising conductors carrying circuit currents in opposite directions, and means for reducing the effect of electromotive forces induced in said conductors from adjacent conductors, comprising a plurality of inductively related windings, one of said windings being connected in each conductor in relation such that the fluxes produced by circuit currents flowing in the different windings neutralize each other whereas currents resulting from said induced electromotive forces produce fluxes in said windings which are not neutralized.

3. In combination, a signal circuit comprising signal equipment located at remote points and a pair of conductors connecting said equipment for carrying signal currents in opposite directions, and means for reducing the effect of electromotive forces induced in both of said conductors in the same direction, comprising inductively related windings connected in each of said conductors, at a plurality of points spaced at equal distances

along said conductors the windings at each point being so related to each other that they offer minimum impedance to signal currents and maximum impedance to currents resulting from said induced electromotive forces.

4. In combination, a pair of electric circuits, each circuit comprising conductors which carry circuit currents in opposite directions, a phantom circuit comprising signal equipment connected between said circuits at both ends thereof whereby both conductors of each of said first mentioned circuits carry phantom circuit currents in the same direction, and means for reducing disturbing currents in said phantom circuit comprising a coil having a plurality of windings, each conductor of both of said circuits including one of said windings and the windings in both conductors of one circuit being in opposed relation to the windings in conductors of the other circuit with respect to phantom circuit currents.

5. In combination, a pair of electric circuits, each circuit comprising conductors which carry circuit currents in opposite directions, a phantom circuit comprising signal equipment connected between said circuits at both ends thereof whereby both conductors of each of said first mentioned circuits carry phantom circuit currents in the same direction, means for reducing disturbing currents in said circuits comprising a coil having a plurality of windings, each conductor of both of said circuits including one of said windings and the windings in both conductors of one circuit being in opposed relation to the windings in conductors of the other circuit with respect to phantom circuit current, and the windings in conductors of each circuit being in opposed relation with respect to circuit currents of the respective circuit.

In witness whereof, I have hereunto set my hand, this 23rd day of February, 1929.
